The ornamental design for a MULTI-COMPARTMENT STORAGE BAG WITH ROUNDED CORNERS, as shown and described.

DESCRIPTION

FIG. 1 is a top, front perspective view of a first embodiment of the MULTI-COMPARTMENT STORAGE BAG WITH ROUNDED CORNERS, showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top, front perspective open view of the first embodiment;

FIG. 8 is a top, front perspective view of a second embodiment of the MULTI-COMPARTMENT STORAGE BAG WITH ROUNDED CORNERS, showing my new design;

FIG. 9 is a rear elevational view thereof;

FIG. 10 is a top plan view thereof;

FIG. 11 is a bottom plan view thereof;

FIG. 12 is a left side elevational view thereof;

FIG. 13 is a right side elevational view thereof;

FIG. 14 is a top, front perspective open view of the second embodiment;

The broken line showings of portions of the MULTI-COMPARTMENT STORAGE BAG WITH ROUNDED CORNERS are for illustrative purposes only to show environment and form no part of the claimed design.
